[57] CLAIM

The ornamental design for a periodontal instrument, as
shown and described.

DESCRIPTION

FIG. 1 is a side elevational view of a periodontal instru-
ment showing our new design;

FIG. 2 is a front elevational view thereof;

FIG. 3 is a bottom plan view thereof;

FIG. 4 is a top plan view thereof;

FIG. 5 is a side elevational view of a second embodi-
ment thereof;

FIG. 6 is a front elevational view thereof;

FIG. 7 is a bottom plan view thereof;

FIG. 8 is a rear elevational view of the first embodi-
ment thereof; and,

FIG. 9 is a rear elevational view of a second embodi-
ment thereof.

The top plan view of the second embodiment is identi-
cal to the top plan view of the original embodiment as
shown in FIG. 4.
